UNITED STATES PATENT OFFICE.

JOHN M. RILEY, OF NEWARK, NEW JERSEY.

OIL-CAN.

SPECIFICATION forming part of Letters Patent No. 350,447, dated October 5, 1886.

Application filed July 19, 1886. Serial No. 208,451. (No model.)

To all whom it may concern:

Be it known that I, JOHN M. RILEY, a citizen of the United States, residing at Newark, in the county of Essex and State of New Jersey, have invented certain new and useful Improvements in Oil-Cans; and I do hereby declare the following to a full, clear, and exact description of the invention, reference being had to the accompanying drawings, which form part of this specification.

This invention has relation to oil-cans of that class known as "feeders," wherein the oil is projected from the spout or nozzle of the can by the depression of a flexible metallic bottom.

My invention has for its object the provision of means for protecting the flexible bottoms of such cans from extraneous injury; and my invention consists in a can with a supplementary metallic bottom or shield having a central orifice for the passage of the thumb or finger, said supplementary bottom being made separate from the can-body and attached to the inner surface thereof directly below the flexible bottom.

Referring to the accompanying drawings, in which my improvement is illustrated, and in which Figure 1 is a vertical sectional view, and Fig. 2 a bottom view, of an oil can with the shield in position thereon, A designates the body of the oiler, which is of metal and of the ordinary or any desired configuration. B designates the flexible bottom by means of which the oil is projected from the can, said bottom being also of the ordinary construction—that is, a circular disk of thin elastic metal slightly dish-shaped and with or without the usual concentric annular beads.

C designates the shield which I attach to the can for the purpose of protecting the bottom B. Said shield consists of a metallic disk or plate of slightly concavo-convex con-

figuration, with a central hole, c, of size sufficient to permit of the passage of the thumb or finger. The shield C is provided with a flange, d, around its edge, which fits nicely within the depending edge a of the body A, and is secured thereto by soldering, brazing, or in any other suitable or desired manner. The shield C is placed at a sufficient distance from the flexible bottom B to permit of the free movement of the latter.

The advantages of my improvement are as follows: In oilers of the ordinary construction the flexible bottom is exposed to contact with sharp corners of machinery, and is liable to become indented, thereby impairing its elasticity, or to be perforated and thereby destroyed.

Where my improved shield is employed the flexible bottom of the can is protected from injury and defacement, and the oiler will consequently remain in better working condition and last longer than if the bottom were exposed.

Having described my invention, I claim—
The improved oil-can having the body made with its lower portion cylindrical, and terminating in an edge upon which the can rests, and having secured to its inner surface above said edge the flexible metallic bottom B, formed with an annular flange, and the supplementary metallic bottom C, having an annular flange and a central flanged orifice, said bottoms being attached by their flanges to the body of the can, as shown and described.

In testimony that I claim the foregoing I have hereunto set my hand this 12th day of July, 1886.

JOHN M. RILEY.
